UNITED STATES PATENT OFFICE.

JOHN E. MOLLE, OF WAUSAU, WISCONSIN.

LINE-SPACING MECHANISM FOR TYPE-WRITERS.

1,081,459.

Specification of Letters Patent.

Patented Dec. 16, 1913.

Original application filed August 3, 1908, Serial No. 446,677. Renewed December 12, 1911, Serial No. 665,378. Divided and this application filed February 10, 1913. Serial No. 747,506.

To all whom it may concern:

Be it known that I, JOHN E. MOLLE, a citizen of the United States, residing at Wausau, in the county of Marathon and State of Wisconsin, have invented a new and useful Line-Spacing Mechanism for Type-Writers, of which the following is a specification.

This invention relates to line spacing mechanism for typewriters and is more particularly a division of an application for United States Letters Patent filed by me on August 3, 1908, Serial No. 446,677, and renewed on December 12, 1911, Serial No. 15 665,378.

One of the objects of the invention is to provide simple and compact mechanism for rotating the platen, said mechanism including an adjusting element whereby the platen 20 can be caused to rotate to shift the paper one or more lines, as desired.

A further object is to provide mechanism of this character utilizing a single spring for holding the adjusting element in any 25 position to which it may be shifted and for holding the pawl and its actuating lever normally in set positions.

With the foregoing and other objects in view which will appear as the description 30 proceeds, the invention resides in the combination and arrangement of parts and in the details of construction hereinafter described and claimed, it being understood that changes in the precise embodiment of 35 the invention herein disclosed can be made within the scope of what is claimed, without departing from the spirit of the invention.

In the accompanying drawings the preferred form of the invention has been shown.

40 In said drawings:—Figure 1 is an end elevation of a carriage having the present improvements combined therewith. Fig. 2 is a plan view of one end portion of the carriage and of the platen shifting mechanism 45 thereon. Fig. 3 is a view similar to Fig. 2 but showing a portion of the mechanism in section, one of the positions of the adjusting cam being indicated by dotted lines. Fig. 4 is a section on line A—B Fig. 3, the restraining dog and the rack shifting lever being 50 shown in section.

Referring to the figures by characters of reference 33 designates a cylindrical platen of the usual or any preferred type, the same 55 being mounted upon a carriage having end

plates one of which is shown at 34. These plates are suitably connected, and arranged back of the platen is a plate 54 constituting a paper guide. A depending bar 60 is pivotally connected to the end plate 34 and carries, at its lower end, a rack bar 61. This bar may be made in one piece with the bar 60 and it is to be understood that, if desired, one of the bars 60 may be located at each end of the carriage. The bar 60 extends upwardly to form a lever 63 the upper end portion of which can be offset to form a thumb piece 64 adjacent the usual manipulating knob 65 of the platen. The foregoing parts constitute no parts of the present invention but have merely been described as forming a part of the structure to which the present improvements are to be applied.

Secured to one of the end plates 34 of the carriage is a bracket 190 which may be formed in a plate bent to form upper and lower leaves or thicknesses each of which is tapered toward its outer end as shown. At the outer ends of these leaves is pivoted a line-spacing lever 191 the free end of which is formed 70 into a thumb piece 192. The short arm of the lever is housed between the two leaves or legs of the bracket 190 and is made up of upper and lower wings between which is pivoted one end of a pawl 193, the other end 75 of which is adapted to engage a ratchet wheel 194 on the platen shaft. A U-shaped strip is pivotally mounted between its ends upon the end plate 34 and constitutes a restraining pawl 195, this pawl carrying a 80 roller 195' which is held constantly in contact with the periphery of the ratchet wheel 194 by a spring 196 as shown particularly 85 in Figs. 1 and 4. A spring 196 is mounted on the pivot 197 of lever 191 and one leg of this spring engages a pin 198 on pawl 193. The other leg of the spring engages a regulating or adjusting lever 199 mounted in the bracket 190. The movement of the lever 191 in the direction urged by the spring 196 is 90 limited by a stop pin 200 carried by the bracket 190.

When the lever 191 is grasped to return the carriage to its initial position, as ordinarily, spring 196 first yields so as to permit 105 said lever to pull on the pawl 193 thereby to cause the ratchet wheel 194 to rotate. The extent of this rotation is determined by the lever 199 which may be shifted to the position indicated by dotted lines in Fig. 3, thus 110

2
to permit only sufficient movement of the pawl to rotate the platen one line space or which can be shifted to the position indicated by full lines in Fig. 3, thereby to permit greater movement of the pawl 193 and lever 191 and correspondingly greater movement of the platen which can thus be rotated two line spaces. It will be apparent that spring 196 operates to hold lever 199 in either of the positions to which it may be shifted and, furthermore, serves to hold the pawl 193 and the lever 191 normally set.

It will be apparent that when the platen and its ratchet wheel 194 are rotated the teeth of the ratchet wheel will escape over the roller 195 carried by the pawl 195 but the spring 196 will press said roller against the ratchet wheel with sufficient force to prevent the platen from rotating too freely.

20 What is claimed is:—

1. In a typewriter, a platen mounted for rotation, a ratchet wheel revoluble therewith, a line-spacing lever movable with the carriage, a pawl connected to said lever 25 adapted to engage the ratchet wheel, a regulating lever adjacent the line-spacing lever and adjustable to either of two positions for limiting the movement of the line-spacing lever and the pawl, and a spring for holding said regulating lever in adjusted position and for holding the pawl and line-spacing lever in normal position.

2. In a typewriter, a carriage, a platen, a ratchet wheel, a line-spacing lever movable with the carriage, a pawl carried thereby, an adjusting lever, and a spring mounted on the pivot of the line-spacing lever and having its legs in engagement with the pawl and adjusting lever respectively to 35 hold the pawl and line-spacing lever in normal positions and to hold the adjusting lever in adjusted position.

3. The combination with a typewriter carriage, a platen mounted to rotate thereon, a ratchet wheel connected with the platen, of a bracket, a line-spacing lever pivotally mounted within the bracket and having spaced wings constituting one arm thereof, a pawl pivotally mounted between the wings, an adjusting lever pivoted with- 40 in the bracket and movable angularly to

limit the movement of the line-spacing lever and pawl in one direction, and a spring mounted on the pivot of the line-spacing lever and having its ends engaging said adjusting lever and the pawl respectively to hold the adjusting lever in any position to which it may be shifted and to hold the pawl and line-spacing lever in normal positions.

55

60

4. Platen rotating mechanism for typewriters, including a ratchet wheel revoluble with the platen, a bracket movable with the carriage, a line-spacing lever fulcrumed within the bracket, a pawl pivotally connected to one arm of said lever, an adjusting lever mounted within the bracket and adjustable angularly to limit the movement of the pawl in one direction, and a spring engaging the pivot of the line-spacing lever 65 and having its legs engaging the pawl and the adjusting lever respectively for holding the pawl normally disengaged from the ratchet wheel and for holding the adjusting lever against accidental movement about its 70 axis.

5. Platen rotating mechanism for typewriters, including a ratchet wheel revoluble with the platen, a bracket movable with the carriage, a line-spacing lever fulcrumed within the bracket, a pawl pivotally connected to one arm of said lever, an adjusting lever mounted within the bracket and adjustable angularly to limit the movement of the pawl in one direction, a spring engaging the pivot of the line-spacing lever and having its legs engaging the pawl and the adjusting lever respectively for holding the pawl normally disengaged from the ratchet wheel and for holding the adjusting lever 80 against accidental movement about its axis, and a stop device extending across the bracket for limiting the movement of the pawl under the action of said spring.

85 In testimony that I claim the foregoing as my own, I have hereto affixed my signature in the presence of two witnesses.

90 JOHN E. MOLLE.
